UNITED STATES PATENT OFFICE

DAVID BOTEN, OF CHICAGO, ILLINOIS

DESIGN FOR A SHOE

Application filed April 20, 1931. Serial No. 39,566. Term of patent 3½ years.

To all whom it may concern:

Be it known that I, DAVID BOTEN, a citizen of the United States, residing at Chicago, in the county of Cook and State of Illinois, have invented a new, original, and ornamental Design for Shoes, of which the following is a specification, reference being had to the accompanying drawing, forming a part thereof, in which the figure is a front perspective view of a shoe showing my new design.

I claim:

The ornamental design for a shoe, as shown.

In testimony whereof I affix my signature at 10 So. La Salle St., Chicago, Ill.

DAVID BOTEN.
